CLAIM

The ornamental design for a radio-frequency spectrum analyzer, as shown and described.

DESCRIPTION

The patent file contains at least one drawing executed in color. Copies of this patent with color drawing(s) will be provided by the Patent and Trademark Office upon request and payment of the necessary fee.

1. Radio-frequency spectrum analyzer
- 1.1 : Front
- 1.2 : Back
- 1.3 : Bottom
- 1.4 : Right side
- 1.5 : Left side
- 1.6 : Top
- 1.7 : Oblique rear view
